UNITED STATES PATENT OFFICE.

OLIVER E. SHAW, OF CHICAGO, ILLINOIS.

CAR-PART.

1,275,312.

specification of Letters Patent. Patented Aug. 13, 1918.

Application filed April 17, 1918. Serial No. 228,989.

To all whom it may concern:

Be it known that I, OLIVER E. SHAW, a citizen of the United States, and resident of Chicago, in the county of Cook and State of Illinois, have invented certain new and useful Improvements in Car Parts, of which the following is a specification.

My invention relates to railway car construction and particularly to an improvement applicable to refrigerator cars.

In the construction of refrigerator cars it is common to build the same with a wooden underframe consisting of center, intermediate and side sills, the center sills being reinforced and strengthened by applying thereto a draft arm extending continuously from the buffer block or end sill to a point a substantial distance to the rear of the bolster one of these arms being applied to each of the center sills. In the construction of such arms a portion is provided which underlies a center sill and a portion which lies alongside of the sill. It is also essential in the construction of such cars that a double floor be provided; that is, in addition to the ordinary floor a sub-floor or wall is located between the sills. The manner of supporting this sub-floor at the point occupied by the draft arm has occasioned considerable difficulty and the present invention relates to the provision of means for readily and securely supporting the floor. The result is secured by providing on the draft arms a laterally projecting shelf or ledge which extends from end to end of the metallic member.

The invention will be more readily understood by reference to the accompanying drawings, wherein;

40. Figure 1 is a side elevation of a draft arm constructed in accordance with my invention;

Fig. 2 is a transverse sectional view on the line 2—2 of Fig. 1, and

45. Fig. 3 is a similar view on the line 3—3 of Fig. 1.

In the drawings the center sills are indicated at 10, and an intermediate sill at 11. A floor 12, of the usual construction is superposed thereon. As a means for supporting the draft rigging and strengthening the wooden center sills, the draft arms, each formed as a massive casting, are applied thereto. These arms each include a draft rigging supporting portion 13, a portion 14, which extends over the bolster, and the por-

tion 15, which is secured to and underlies the sill at the rear of the bolster. It will be noted that the casting has a vertical web which lies alongside of the center sill and extends from the end sill 16, to a point a substantial distance to the rear of the bolster. On this vertical web I cast an integral, laterally projecting ledge 17, adapted, as best shown in Figs. 2 and 3, to support a sub-floor 18, the opposite end of the floor boards being supported on a projection 19, carried by the intermediate sill 11. The ledge will be so positioned as to overlie with sufficient clearance the truss rod saddle 20, and underlie the strengthening flange 21, which projects from the portion 14.

By the use of this construction all fitting of boards around the reinforcing casting is avoided. If it be desired to securely fasten the boards to the casting, bolts may be passed through the boards and the ledge in the usual manner.

I claim:

1. In a railway car, the combination with adjacent longitudinal sills of a metal reinforcing member for one of said sills, said member being provided with a laterally projecting ledge, and an insulating floor supported at one side on said ledge and at another side on the side of an adjacent sill, substantially as described.

2. In a railway car, the combination of longitudinal wooden sills, a metal reinforcing member extending alongside of one of said sills to a point to the rear of the bolster, said member being provided with a metal ledge projecting from the side and extending substantially from end to end thereof, and a sub-floor between said sills and supported on said ledge, substantially as described.

3. In a double floor car, the combination of wooden center and intermediate sills, a metal reinforcing member lying alongside of a center sill and extending rearwardly a substantial distance from the end of the car, said member being provided with an integral, laterally projecting ledge, the lower floor boards being supported on said ledge and the side of the adjacent intermediate sill, substantially as described.

4. A draft arm in the form of a casting adapted to lie alongside of a wooden sill and to extend a substantial distance rearwardly from the end of the car, said casting being provided with an integral, lateral

ledge extending substantially from end to end of the casting and adapted to support sub-floor boards, substantially as described.

5. In an insulated ear, the combination of 3 wooden center and intermediate sills, a floor laid thereon, a metal draft arm lying alongside of a center sill on the side toward an intermediate sill, said arm being in the form of a casting having an integral side ledge 10 located at a point intermediate of its height

and extending substantially from end to end thereof, and an insulating floor supported on said ledge and the adjacent intermediate sill, substantially as described.

Signed at Chicago, Ill., this 8th day of 15 April, 1918.

OLIVER E. SHAW.
